C. A. SMITH.
GEAR PUMP AND THE LIKE.
APPLICATION FILED OCT. 11, 1917.

1,285,819.

Patented Nov. 26, 1918.

UNITED STATES PATENT OFFICE.

CHARLES A. SMITH, OF HOPEDALE, MASSACHUSETTS, ASSIGNOR, BY MESNE ASSIGNMENTS, TO HOPEDALE MANUFACTURING COMPANY, OF MILFORD, MASSACHUSETTS, A CORPORATION OF MASSACHUSETTS.

GEAR-PUMP AND THE LIKE.

1,285,819.

Specification of Letters Patent. Patented Nov. 26, 1918.

Application filed October 11, 1917. Serial No. 196,045.

To all whom it may concern:

Be it known that I, CHARLES A. SMITH, a citizen of the United States, residing at Hopedale, in the county of Worcester and State of Massachusetts, have invented an Improvement in Gear-Pumps and the like, of which the following description, in connection with the accompanying drawings, is a specification, like characters on the drawings representing like parts.

The invention hereinafter described relates to gear pumps and other rotary engines, and among other objects provides simple and effective means for compensating for wear on the parts thereof and increasing their efficiency.

These and other objects of the invention will be more fully described in the following description of one good form of means shown in the accompanying drawings for carrying the invention into practical effect, it being understood that the invention in its true scope is not limited to the details thereof, but as defined by the appended claims.

In the drawings:—

Figure 1 is a vertical section through a gear pump shown herein to illustrate the invention;

Fig. 2 is a vertical transverse section taken on the broken line 2—2; and

Fig. 3 is a vertical transverse section taken on the broken line 3—3 of Fig. 1.

Referring to the drawings:—The gear pump shown therein as embodying the invention comprises a casing having a body 1 and a head 3 detachably connected to said body by screws 4.

A pair of intermeshing gears 5 and 6 are mounted in said casing, the latter being formed to present an elliptic-like chamber 7 having its upper and lower ends curved on a radius corresponding to the radius of said gears, the construction being such that the gears will have a close rotary contact with the curved ends of said chamber.

The casing may have an inlet 9 communicating with a supply pipe 11 connected to a boss 13 of the casing, and the casing may have an outlet 16 communicating with a discharge pipe 15 connected to a boss 17 on the casing.

The construction is such that as the gears revolve in the directions indicated by the arrows, the spaces 18 between the teeth of

the gears will coöperate with the curved ends of the chamber to exhaust air from the inlet and feed pipe. When the air is sufficiently exhausted, atmospheric pressure will force the liquid from the feed pipe into the pump casing. The liquid then fills the spaces between the gears and is carried around and delivered thereby to the outlet and discharge pipe.

To produce a constant pressure of discharge, a by-pass between the inlet and outlet may be provided comprising vertical ports 19 and 21 extending downward from said inlet and outlet respectively, and communicating with a horizontal port 23 in said casing beneath said chamber. This horizontal port may be reduced intermediate its ends and present a valve-seat 27. A ball-valve 29 is urged toward said seat by a helical spring 31 confined between said ball-valve and a plug 33 closing one end of said horizontal port, the opposite end of said port being closed by a similar plug 35.

If the pressure tends to build up at the outlet the liquid will pass back from said outlet into the by-pass, forcing the ball-valve from its seat, and passing thence from the by-pass to the inlet.

In the operation of gear-pumps, the principal wear comes upon the end faces of the gears and the walls engaged thereby. Next will be described means for preventing end play of the gears and for compensating for wear on the parts referred to.

To accomplish this, in the present instance of the invention, the gears are offset axially so that the end faces of one of the gears are in different planes from the end faces of the other gear. The end 37 of the upper gear projects outward beyond the corresponding end 39 of the lower gear, and the end 41 of the lower gear projects outward beyond the corresponding end 41 of the upper gear.

The outwardly projecting ends 37 and 41 extend into recesses 47 of a diameter corresponding to the diameter of said gears. The recess for the upper gear may be formed in the body of the casing while the recess for the lower gear may be formed in the head of the casing.

Suitable movable members may be mounted in said recesses and be adapted to engage the ends of said gears to prevent end play

and to take up the wear on the parts. In the present instance of the invention, these members are in the form of collars 49 fitting said recesses and having stems 61 projecting 5 outward in counterbores 53 in said casing and head. To press said collars automatically toward said gears they may be provided with helical springs 55 encircling reduced ends 57 of said stems and confined 10 between shoulders of said stems and caps 59 threaded to the outer ends of said counterbores. To prevent rotation of said stems screw keys 51 may be tapped into said head and casing and have reduced ends projecting 15 into grooves 63 in said stems.

The upper gear may be provided with stud shafts 65 journaled in bearings in its spring-pressed collar and the head of said casing. The lower gear may be provided 20 with a stud shaft 67 and a shaft 68 journaled in bearings in its spring-pressed collar and casing respectively. The shaft 68 projects outward beyond the casing to receive a driving pulley 69. To prevent leakage 25 from the casing along said shaft it may be provided with a stuffing box comprising suitable packing and a gland 71 secured to the casing by suitable screws, (not shown).

Since the gears have offset end faces, the 30 spring-pressed collars may completely cover said faces without limitation or interference from the other end faces of the gears and will be able to move in said recesses to take up end play of the gears and compensate for 35 wear on the end faces of the gears and the walls engaged thereby. In the present instance of the invention this movement of the collars is accomplished automatically by the springs acting thereon.

40 In use, the gears may wear different amounts, but the construction is such that the wear on each gear may be taken up independently of the other and thus no opportunity for end play is left on either gear.

45 The by-pass and valve 29 are not indispensable, since excess pressure built up at the outlet may force the members 49 axially outward against the resistance of their springs, away from the ends of the pump 50 gears, and permit the fluid to pass between said members and ends toward the inlet, thereby relieving the excess pressure. The springs, however, are stiff enough to prevent the members from moving from said ends 55 under normal pressure, and consequently, prevent leakage between them at such times.

It will be understood that the invention is not limited to gear pumps, but that it is applicable to eccentric pumps and other embodiments of rotary engines.

What is claimed is:—

1. A device of the character described, comprising, in combination, a casing having curved walls, intermeshing gears fitting said 65 curved walls and axially offset relatively to

one another so that an end of each projects beyond the corresponding end of the other, follower members for engagement with the projecting ends of said gears and covering the ends of the teeth and the spaces between 70 the teeth at the projecting ends of the gears, and means tending to press said follower members against the ends of said gears automatically to take up wear and prevent leakage at the ends of the teeth of said gears. 75

2. A device of the character described, comprising, in combination, a casing having curved walls, intermeshing gears fitting said curved walls and axially offset relatively to one another so that an end of each 80 projects beyond the corresponding end of the other, follower members having areas sufficient to cover the ends of the teeth and the spaces therebetween at the projecting ends of the gears, and spring means acting 85 on said follower members for pressing the same against the ends of said gears.

3. A device of the character described, comprising, in combination, a casing, intermeshing gears therein axially offset relatively to one another so that an end of each projects beyond the corresponding end of the other, follower members for engagement with the projecting ends of said gears and at least equal to the diameters of said gears, 90 said members being adjustable to take up wear between the ends of the gears and the surfaces engaged thereby, and means to drive one of said gears.

4. A device of the character described, 100 comprising, in combination, a casing, intermeshing gears therein axially offset relatively to one another so that an end of each projects beyond the corresponding end of the other, follower members having collars 105 for engagement with the projecting ends of said gears and at least equal to the diameters of said gears, and spring means for pressing said collars toward said projecting ends to maintain a close working fit between them. 110

5. A device of the character described, comprising, in combination, a casing, intermeshing gears therein axially offset relatively to one another so that an end of each projects beyond the corresponding end of the other, follower members at least equal 115 to the diameters of said gears and having bearings therein, shafts for said gears journaled in said bearings, and means for adjusting said followers along said shafts into intimate working engagement with said projecting ends.

6. A device of the character described, comprising, in combination, a casing, intermeshing gears therein axially offset relatively to one another so that an end of each projects beyond the corresponding end of the other, follower members at least equal to the diameters of said gears, said casing having chambers receiving said follower mem- 125 130

bers, removable closures for said chambers, and springs confined between said closures and follower members for pressing the latter toward said gears.

5 7. A device of the character described, comprising, in combination, a casing having a body and a head, means detachably connecting said head to said body, intermeshing gears in said casing axially offset relatively 10 to one another so that an end of each projects beyond the corresponding end of the other, follower members for engagement with the projecting ends of said gears and of areas sufficient to cover ends of the teeth of said 15 gears, one of said follower members being mounted in the casing body, and the other follower member being mounted in said head, and springs acting on said follower members for pressing the same into intimate 20 engagement with the projecting ends of the gears to prevent leakage between the parts.

8. A device of the character described, comprising, in combination, a casing having an inlet and an outlet, intermeshing gears 25 mounted in said casing for feeding fluid from said inlet to said outlet, said gears being axially offset relatively to one another, so that an end of each projects beyond the

corresponding end of the other, follower members covering the ends of the teeth at 30 the projecting ends of said gears, and means tending continuously to press said follower members against said projecting ends to prevent leakage between said inlet and outlet around the paths of rotation of said gears. 35

9. A device of the character described, comprising, in combination, a casing having an inlet and an outlet, a pair of intermeshing gears mounted in said casing for feeding fluid from said inlet to said outlet, said gears 40 being axially offset relatively to one another so that an end of each projects beyond the corresponding end of another, said casing having a by-pass connecting said inlet and outlet, valve means for said by-pass to relieve pressure at said outlet, follower members for engagement with the projecting ends of said gears, and at least equal to the 45 diameters of said gears, spring means for pressing said follower members toward the projecting ends of said gears, and means for driving one of said gears.

In testimony whereof, I have signed my name to this specification.

CHARLES A. SMITH.
